WELL TRAP

Arthur F. O'Connor, Chicago, Ill., assignor to
 Equipment Specialties Company, Chicago, Ill.,
 a corporation of Illinois

Application July 14, 1931. Serial No. 550,683

5 Claims. (Cl. 182—8)

My invention relates in general to traps and has more particular reference to a well trap adapted for use in railroad refrigerator cars and other refrigeration apparatus. Refrigerator cars are ordinarily provided with drains for the melted refrigerant, condensed and other moisture, which may collect inside the refrigerator compartment.

An important object of the invention is to provide a trap for normally sealing the drain to prevent the ingress of relatively hot air through the drain while permitting the egress of such moisture or fluid as may be required to be drained out of the compartment.

Refrigerator cars and like apparatus are frequently utilized, during the winter months, as heated transport means for merchandise which deteriorates when cooled below a certain critical temperature. For such use, means is provided for heating the insulated compartment in which the goods are carried and it is necessary in the interest of economical operation to prevent the ingress of cold air through the drains. In a heated compartment of the class mentioned, there will be little, if any, moisture to be drained and so the trap formed in the drain cannot rely upon the fluid to be drained to form a fluid seal and it is another important object of my invention to provide a trap of the class described, which will seal the drain against the ingress of air even when there is no fluid to be drained, said trap being instantaneously operable to drain out the fluid in excess of a maximum quantity as soon as the same accumulates at the drain.

Another object is to provide a simple, inexpensive, easily manufactured, drain trap of the class described, of rugged construction and well adapted to furnish positive operation in service and to be easily assembled in operative position as in the floor of an insulated railroad refrigerator car.

Numerous other objects and advantages of the invention will be more fully understood from the following description, which, taken in connection with the accompanying drawing, discloses a preferred embodiment of my invention.

Referring to the drawing:

Figure 1 is a top plan view of a drain and trap embodying my present invention; and

Figure 2 is a vertical section taken substantially along the lines 2—2 in Figure 1.

To illustrate my invention, I have shown a drain and a drain trap comprising means forming a sump or receptacle 11 in which fluid to be drained may be collected. This receptacle may, of course, be formed in any suitable manner but I prefer to provide the same in the form of a

fitting 13 adapted to be set in an opening 15 formed preferably in the floor 17 of the compartment to be drained, which may be and preferably is the ice or refrigerant compartment of a railroad refrigerator car, although, of course, the well trap has other application and may be used for the purpose of draining other than refrigerators.

The fitting 13 preferably comprises an annular flange 19, by which to secure the device in place, the flange preferably having a plurality of circularly arranged, spaced-apart perforations 21 therein, through which suitable fastening means (not shown), such as nutted bolts, rivets and the like, may extend in order to secure the fitting on the portion to which it is mounted. The fitting is usually and preferably fastened to a drain pan 18, which is or may be supported on or by the floor 17 and the flange also may be welded to the pan 18 if expedient and in such case, the perforations 21 may be omitted. The fitting 13 also comprises a center bowl 23 preferably formed integrally with the flange 19, the fitting being of such a shape that it may be formed very cheaply as a sheet metal punching, although, of course, the fitting may be formed as a casting if desired.

The bowl 23 is provided with a preferably central opening 25 in its bottom, through which extends a drain pipe 27, the upper end 29 of which projects within the bowl 23, terminating a short distance above the bottom thereof and providing an upwardly facing drain opening 31 within the bowl. The drain pipe 27 preferably fits snugly within the bowl opening 25 and is preferably secured in place by a continuous weld 32 extending completely around the pipe at the insertion thereof with the inner surface of the bottom of the bowl 23. The pipe 27 is also secured and sealed in place by means of the spaced-apart welds 33 on the outer surface of the bowl bottom at the edge of the opening 25.

The drain trap also comprises a float 35 comprising a hollow, hermetically sealed shell, preferably of sheet metal, the lower face of which is provided with a central, downwardly embossed seat 37 and a peripheral bead 39 encircling and extending downwardly substantially below the surface of the embossed portion 37. The shell, comprising the float 35, is provided with a pair of registering perforations 41 in its upper and lower walls, the perforation in the lower wall being preferably centrally located with respect to the embossed portion. These perforations 41 are of sufficient size to receive a pintle 43, which

is sealed in position preferably by circles of solder or other suitable sealing means 45, which sealing means also operates to hermetically close the perforations 41 around the pintle 43.

- 5 The pintle has a lower end 47 extending substantially downwardly of the surface of the embossed portion and an upper end 49 extending substantially upwardly of the upper wall of the float casing 35. The lower projecting end 47 of the pintle carries a rubber disk 51 having a preferably central perforation 53 through which the pintle extends, the rubber disk 51 being held against the boss 37 by means of a washer 55 of steel or other suitable material, which is held on the end of the pintle by means of a cotter or split pin 57, or other suitable fastening means, the pintle 47 being provided with a diametrical bore 59 to receive the pin.

- 20 The float is arranged in the fitting 13 with the axis of the pintle 43 in substantial alignment with the pipe 27, the rubber washer 51 being seated upon the upper edge 29 of the pipe and substantially closing and sealing the pipe opening 31. In order to hold the float and associated elements 25 in pipe sealing position, the upper projecting end 49 of the pintle extends loosely through a relatively large perforation 61 formed in a preferably metal strap 63, which is laid across the fitting 13 with its opposite ends resting upon the flange 19. The strap 63 is held in place with the opening 61 in substantially vertical alignment with the opening 31 in position to receive the end 49 of the pintle. For this purpose the opposite ends of the strap 63 are provided with perforations 67 adapted to receive pins 65 fastened to and extending upwardly of the flange 19. The pins 65 are provided with preferably diametrical channels to receive split pins or other fastening means (not shown) in order to hold the strap 40 63 in place.

- In operation, the fluid to be drained gradually accumulates in the sump 11. The weight of the float, pintle and sealing gasket 51 is ordinarily sufficient to press the gasket firmly against the 45 upper open end of the drain pipe 27 so that the same is normally sealed against the ingress of warm air or the egress of cold air through the drain pipe. This condition prevails when the sump is empty and until sufficient fluid accumulates in the sump to raise the float slightly. The depending peripheral bead 39 formed in the float extends, when the float is in normal pipe-sealing position, substantially below the upper end of the pipe and the float will ordinarily not 50 be raised from pipe sealing position until the fluid level has risen above the lowermost portion of the depending bead 39, that is to say, until a water-seal is formed, and I prefer to form the float and its associated apparatus sufficiently 55 heavy to prevent the float from being raised from pipe sealing position until the fluid level has reached the upper end of the drain pipe, a level indicated by the dotted line 71 in Figure 2 of the drawing, substantially above the bottom of the bead 39.

- Any increase in the amount of fluid in the sump above that critical amount indicated by the dotted line 71, therefore results in raising the float and permitting the excess to drain off into 70 the pipe 27 between the raised gasket 51 and the upper end of the pipe. It will be apparent that, when the float and attached gasket 51 are raised, the float, on account of the depending peripheral bead 29, which encircles the gasket and the upper end of the pipe, together with the fluid on

which the float is supported, will form a fluid seal for the pipe, which seal will substantially prevent the ingress or egress of air or other gas through the drain.

The device of my present invention is therefore adapted to form a mechanical seal at all times when the fluid level in the sump is below a predetermined critical elevation and when the level exceeds this critical point, the mechanical seal will be broken to permit the escape of excess fluid while the parts co-operate to form a fluid seal at such times so that the trap at all times prevents the passage of air and other gases while permitting the escape of excess fluid.

It is thought that the invention and numerous of its attendant advantages will be understood from the foregoing description and it is obvious that numerous changes may be made in the form, construction, and arrangement of the several parts without departing from the spirit or scope of my invention or sacrificing any of its attendant advantages; the form herein described being a preferred embodiment for the purpose of illustrating my invention.

Having thus described my invention, what I claim as new and desire to secure by Letters Patent is as follows:

1. In a well trap, means forming a liquid pocket having an upwardly open overflow outlet, a float having a portion overlying and normally sealing said outlet and a depending hollow portion extending below the level of said sealing portion whereby a liquid-seal may be provided as the liquid level in the pocket reaches said portion, said portion being adapted to buoy up the float as the liquid level rises above the level at which the liquid-seal is formed in order to open the outlet for the escape of liquid.

2. In a well trap, means forming a liquid pocket, means forming an upwardly opening overflow outlet in said pocket, means forming a closure for said outlet comprising a float in said pocket comprising a hollow shell-like member having a central axial pin extending therethrough, a downwardly extending embossment formed in the lower surface of said float adjacent the lower projecting end of said pin, an outlet sealing disk or plate seated on said embossment and encircling said pin, fastening means carried by said pin to secure the sealing member upon the embossment, said float being also formed with an annular hollow portion formed in the float outwardly of the embossment and depending substantially below the sealing member, and means to support the float in the liquid pocket with the sealing member in position extending across the upwardly opening overflow outlet.

3. In a well trap, means forming a liquid pocket having an upwardly open over-flow outlet, a float in said pocket, and an outlet-sealing gasket carried by said float in position to overlie and normally seal said outlet, said float having a depending hollow portion extending below the level of said outlet when the float is in normal outlet sealing position whereby a liquid seal may be provided as the liquid level in said pocket reaches said portion, said portion being adapted to buoy up the float and raise the outlet-sealing gasket as the liquid level rises in the pocket above the level at which the liquid seal is formed in order to open the outlet for the escape of the liquid while preventing the escape of gases.

4. In a well trap, means forming a liquid pocket having an upwardly open over-flow outlet, a

float comprising a shell-like member having a portion overlying said outlet and having projecting means extending downwardly centrally of said portion, and an outlet-sealing gasket of resilient material carried by said projecting portion and seated on said portion in position to normally seal said outlet, means carried by the projecting means to hold the gasket in place upon the portion, said float having a hollow portion encircling and extending below the level of said gasket whereby a liquid-seal for the outlet is provided when the liquid level in the pocket reaches said hollow portion, said hollow portion being adapted to buoy up the float and shift the sealing gasket to open the outlet when the liquid level rises in the pocket above the level at which the liquid seal is formed.

5. In a well trap, means forming a liquid pocket, means forming an upwardly open over-flow outlet in said pocket, a float in said pocket

comprising a hollow shell-like member, said shell-like member having downwardly facing embossment formed in its lower surface, said embossment being of lesser size than the over-flow outlet, and a resilient outlet sealing gasket mounted on said embossment and having edges projecting outwardly of the edges of the embossment in position to sealingly engage the edges of the over-flow outlet, said float being also formed with a portion extending outwardly of and below the sealing gasket and encircling the over-flow outlet whereby a liquid seal for the outlet may be provided when the upper level of liquid in the pocket reaches said portion, said portion serving to raise the float in the pocket and lift the sealing gasket from the over-flow outlet when the liquid level rises above the level at which the liquid seal is formed whereby to open the outlet for the escape of liquid.
